UNITED STATES PATENT OFFICE.

WILLIAM E. SCHNEIDER, OF WASHINGTON, DISTRICT OF COLUMBIA.

DESIGN FOR AN AUTOCARETTE-BODY.

SPECIFICATION forming part of Design No. 35,984, dated July 29, 1902.

Application filed April 11, 1902. Serial No. 102,485. Term of patent 14 years.

To all whom it may concern:

Be it known that I, WILLIAM E. SCHNEIDER, a citizen of the United States, residing at Washington, in the District of Columbia, have invented a new, original, and ornamental Design for an Autocarette-Body, of which the following is a specification, reference being had to the accompanying drawings, forming part thereof, in which—

Figure 1 is a perspective front and side view, and Fig. 2 is a perspective rear and side view, of a body embodying my new design.

The design comprises the general ornamentation and configuration of the autocarette-body shown in the drawings, in which A represents the body, of a generally rectangular form, having an upwardly-projecting top narrower than the body, inwardly-sloping sides A', a lower front extension B, provided with

a dashboard, a partly-inclosed extension B², 20 having a projecting roof B', a downward extension C, an overhanging top C, and sides C², and parallel bars D D' beneath the body, the whole ornamented and shaped substantially as illustrated in the drawings. 25

Having described my invention, what I claim as new, and desire to secure by Letters Patent, is—

The ornamental design for an autocarette-body, substantially as shown and described. 30

In testimony whereof I have signed my name to this specification in the presence of two subscribing witnesses.

WILLIAM E. SCHNEIDER.
